UNITED STATES PATENT OFFICE.

RAYMOND W. BURNS, OF POUGHKEEPSIE, NEW YORK, ASSIGNOR TO JAMES L. TAYLOR
MFG. CO., A CORPORATION OF NEW YORK.

CLAMP.

Application filed November 2, 1922. Serial No. 598,469.

To all whom it may concern:

Be it known that I, RAYMOND W. BURNS, a citizen of the United States, and a resident of Poughkeepsie, in the county of Dutchess 5 and State of New York, have invented new and useful Improvements in Clamps, of which the following is a specification.

This invention relates more particularly to an end clamping attachment for clamping 10 means for engaging the side edges of a piece of work, such as a plurality of bar clamps positioned in the same plane, as for example one of the series of clamps which receives a piece of work in a clamp carrier. The invention is illustrated in the drawings as applied to such a series of clamps of a clamp carrier, but I desire it understood that the use of the invention is in no way restricted to a clamp carrier, but it can be applied to 15 clamps positioned by any suitable means other than those of a clamp carrier; nor is the number of clamps material, as the invention could be applied to a single clamp.

The objects of the invention are to enable 20 a piece of work clamped at two opposite edges to be readily clamped at two other opposite edges or in a direction at right angles to the first-mentioned clamp; to thus facilitate framing doors, panels, piano ends and 25 various kinds of other work, end veneering and so forth; to provide such end clamping means as an attachment for a clamp carrier; to mount the end clamps upon the other clamps so that they are always in 30 place ready for use and yet not in the way of other work which requires clamping only at the side edges; to secure a simple and convenient adjustment of the end clamps to meet various requirements, and to obtain 35 other advantages and results as may be brought out by the following description.

Referring to the accompanying drawings, in which like numerals of reference indicate 40 the same parts throughout the several views, Figure 1 is a front view of a series of clamps provided with my improved end clamping attachment;

Figure 2 is a side view of the same;

Figure 3 is an underneath view of a portion 45 of the same;

Figure 4 is a cross-section on line 4—4 of Fig. 3, with the parts restored to the work receiving position shown in Figs. 1 and 2, and

Figure 5 is a cross-section on line 5—5 of Fig. 4.

In the specific embodiment of the invention shown in said drawings, the reference numerals 1, 2, 3 and 4 indicate bar clamps attached at one end to the cross-rod 5; 6 of a clamp carrier or machine, as by means of feet 7 one on each bar clamp and engaging said cross-rod by means of bearings 8, 9. For convenience these bar clamps are of the type shown in pending application Serial No. 508,029, filed August 10, 1922, and each has opposite fixed and adjustable jaws 10 and 11, respectively, adapted to be clamped together by means of a handled nut 12 at the free end of the clamp, 70 said jaws being mounted upon angle bars 13 and 14 having two of their flanges parallel and vertical and the other two diverging in the same plane to form a work support. It will be understood that a piece of work 75 such as a door, desk-top or the like, lies flat upon such work supporting surfaces of all the clamps of the series and is engaged at its opposite side edges by the jaws 10 and 11 to clamp the work.

Very often it is desired to clamp the other two or end edges of a piece of work at the same time the side edges are being clamped, and it is the purpose of my invention to provide means for doing this. I therefore arrange beneath the side clamps already described the bars 15, 15 of end clamps, which I have shown as two in number, although as many more may be employed as desired, or indeed one could be employed. Each of 80 said bars 15 is provided at one of its ends with an adjustable jaw 16 which projects upward above the plane of the work supporting flanges of the side clamps, so as to engage one end edge of the work, and at 85 its other end said bar is provided with an adjustable jaw 17 having clamping means, such as the screw 18, also projecting above the plane of said flanges to engage the other end edge of the work. Obviously when 90 said end clamps are properly supported upon the side clamps, so as to be adjustable with respect thereto while preserving a right angular relation, the work can be clamped 95 at all four edges.

I prefer to employ such supporting means depending from the end ones of the series of side clamps, and furthermore from the

outer work supporting flange thereof, so as to be more conveniently accessible. I have shown two such supporting means, although more could be employed, and a description of one will suffice for both. Two light channel bars 19, 20 in parallel relation to each other with their flanges toward each other, are secured to the underside of a work supporting flange by any suitable means such as 10 screws 21 extending through the work-supporting flange and the flanges of the channel bars, as shown in Figure 4. The slide-ways formed by these channel bars may be of any desired length, determined by the 15 distance of adjustment of the end clamps longitudinally of the side clamps. Bolts 22 depend from said channel bars 19, 20, one for each end clamp, the square head 23 of each bolt lying in the space between the webs 20 of the channel bars 19, 20 so as not to turn, and the threaded shank 24 depending through the slot between the lower flanges of said channel bars. Each threaded shank of a bolt carries at its lower end a clevis 25 having a slot 26 to receive the bar 15 of an 25 end clamp and slidably support the same, so that by this means said bars are supported so that they can slide in their clevises 25 for clamping purposes and can be adjusted 30 lengthwise of the carrier clamps by sliding said clevises longitudinally of the channel bars 19, 20.

Between each of the clevises 25 and its channel bars 19, 20 is a peripherally handled nut 27 which can be screwed upward to 35 clamp the bolt 22 against adjustment or movement, and preferably between said nut 27 and channel bars 19, 20 is a binder 28 which is perforated to loosely receive the bolt 22 and has at its opposite ends flanges 29 to engage the opposite outer sides of the lower ends of the channel bars 19, 20 and hold them against moving apart as the bolt 22 is clamped in relation to said channel 40 bars.

By the means thus described, end clamps are supported upon the main or side clamps so as to be in place for use when desired and yet not in the way of work which does not 45 require them. Furthermore, such end clamps can be adjusted longitudinally of the main or side clamps, as desired, and every manipulation of said end clamps can be performed quickly, conveniently and accurately. In the detail construction of said end 50 clamps various modifications can be made without departing from the spirit and scope of the invention, and I do not wish to be understood as limiting myself in any respect except as required by the following claims when construed in the light of the prior art.

Having thus described the invention, what I claim is:

1. The combination with a plurality of 55 bar clamps for engaging the side edges of a

piece of work, of an end bar clamp having its bar beneath the bars of said first-mentioned clamps and supported thereon.

2. The combination with a plurality of 60 bar clamps for engaging the side edges of a piece of work, of an end bar clamp having its bar beneath the bars of said first-mentioned clamps and slidably supported thereon.

3. The combination with a plurality of 65 bar clamps for engaging the side edges of a piece of work, of an end bar clamp having its bar beneath the bars of said first-mentioned clamps and supported thereon so as to slide longitudinally thereof.

4. The combination with a plurality of 70 bar clamps for engaging the side edges of a piece of work, of an end bar clamp having its bar beneath the bars of said first-mentioned clamps and supported thereon so as to slide both longitudinally and transversely 75 thereof.

5. The combination with a plurality of 80 relatively adjustable bar clamps for engaging the side edges of a piece of work, of an 85 end bar clamp having its bar beneath the bars of said first-mentioned clamps and adjustably supported thereon.

6. The combination with a plurality of 90 relatively adjustable bar clamps for engaging the side edges of a piece of work, of an 95 end bar clamp having its bar beneath the bars of said first-mentioned clamps and supported thereon so as to adjust longitudinally thereof.

7. The combination with a plurality of 100 relatively adjustable bar clamps for engaging the side edges of a piece of work, of an end bar clamp having its bar beneath the bars of said first-mentioned clamps and supported thereon so as to adjust both longitudinally and transversely thereof.

8. The combination with a plurality of 105 bar clamps in substantially the same plane, of a bar clamp in a plane adjacent the plane 110 of said plurality of clamps and transverse to the individual clamps of said plurality, and a plurality of connecting means each on a clamp of said plurality of bar clamps and slidably engaging the transverse bar clamp.

9. The combination with a plurality of 115 bar clamps in substantially the same plane, of a bar clamp in a plane adjacent the plane of said plurality of clamps and transverse to 120 the individual clamps of said plurality, and a plurality of connecting means each on a clamp of said plurality of bar clamps and slidably engaging the transverse bar clamp.

10. The combination with a plurality of 125 bar clamps in substantially the same plane, of a bar clamp in a plane adjacent the plane of said plurality of clamps and transverse to 130 the individual clamps of said plurality, and a plurality of connecting means each

- slidable on a clamp of said plurality of bar clamps and slidably engaging the transverse bar clamp.
11. The combination with a plurality of bar clamps in substantially the same plane and each having a longitudinal slideway, of a bar clamp in a plane adjacent the plane of said plurality of clamps and transverse to the individual clamps of said plurality, and a sliding member projecting from each of said slideways and engaging said transverse bar clamp.
12. The combination with a plurality of bar clamps in substantially the same plane and each having a longitudinal slideway, of a bar clamp in a plane adjacent the plane of said plurality of clamps and transverse to the individual clamps of said plurality, and a sliding member projecting from each of said slideways and slidably engaging said transverse bar clamp.
13. The combination with a plurality of bar clamps in substantially the same plane and each having a longitudinal slideway, of a bar clamp in a plane adjacent the plane of said plurality of clamps and transverse to the individual clamps of said plurality, a sliding member projecting from each of said slideways and means for releasably locking said sliding member against sliding.
14. The combination with a bar clamp whose bar has an angle bar with one flange adapted to support the work upon one side of itself, of a bar clamp transverse to said angle bar and in a plane parallel to said work supporting flange, and means on said work-supporting flange at the opposite side from its work supporting side for slidably connecting the bars of said clamps.
15. The combination with a clamp having an angle bar with one flange forming a work-support, of a bar clamp transverse to said angle bar, a longitudinal slideway on said work-supporting flange, and means projecting from said slideway and engaging the bar of the transverse clamp.
16. The combination with a side clamp having an angle bar with one flange forming a work-support, of an end clamp having a bar transverse to said angle bar and spaced from said work-supporting flange by the other flange, a clevis engaging the bar of the end clamp, and means between said clevis and work-supporting flange for slidably connecting them.
17. The combination with a side clamp having an angle bar with one flange forming a work-support, of an end clamp having a bar transverse to said angle bar and spaced from said work-supporting flange by the other flange, a slideway on said work-supporting flange, a bolt slidable in said slideway, and a member on said bolt engaging the bar of the end clamp.
18. The combination with a side clamp having an angle bar with one flange forming a work-support, of an end clamp having a bar transverse to said angle bar and spaced from said work-supporting flange by the other flange, a slideway on said flange, a bolt slidable in said slideway, a member on said bolt engaging the bar of the end clamp, and means for locking said bolt against sliding.
19. The combination with a side clamp having an angle bar with one flange forming a work-support, of an end clamp having a bar transverse to said angle bar and spaced from said work-supporting flange by the other flange, a slideway on said flange, a bolt slidable in said slideway, a member on said bolt engaging the bar of the end clamp, and a nut on said bolt for locking it against sliding.
20. The combination with a side clamp having an angle bar with one flange forming a work-support, of an end clamp having a bar transverse to said angle bar and spaced from said work-supporting flange by the other flange, channel irons depending from said work-supporting flange and forming a slideway, a bolt slidable in said slideway, a nut on said bolt for clamping it against sliding, and a member on said bolt engaging the bar of the end clamp.
21. The combination with a side clamp having an angle bar with one flange forming a work-support, of an end clamp having a bar transverse to said angle bar and spaced from said work-supporting flange by the other flange, channel irons depending from said work-supporting flange and forming a slideway, a bolt slidable in said slideway, a nut on said bolt for clamping it against sliding, a binder between said nut and channel irons to prevent spreading of the latter, and a member on said bolt engaging the bar of the end clamp.
22. The combination with a clamp having spaced bars and an adjustable jaw on said bars with a foot extending therebetween and engaging the opposite edges of said bars, of an end clamp transverse to the said first-mentioned clamp at the opposite side of the spaced bars from the adjustable jaws, and means supporting said end clamp on said spaced bars in such spaced relation thereto as to allow said foot to pass.

RAYMOND W. BURNS.
